UNITED STATES PATENT OFFICE.

HERBERT E. VAN DORN, OF CHICAGO, ILLINOIS.

PNEUMATIC CONTROL SYSTEM FOR ELECTRIC SWITCH AND CAR, AIR, AND ELECTRIC COUPLERS.

Application filed October 3, 1921. Serial No. 505,136.

To all whom it may concern:

Be it known that I, HERBERT E. VAN DORN, a citizen of the United States, residing at Chicago, county of Cook, State of Illinois, have invented a certain new and useful Improvement in Pneumatic Control Systems for Electric Switch and Car, Air, and Electric Couplers, and declare the following to be a full, clear, and exact description of the same, such as will enable others skilled in the art to which it pertains to make and use the same, reference being had to the accompanying drawings, which form a part of this specification.

In my prior application Serial No. 489,953 filed August 5, 1921, I have disclosed a novel pneumatic control system for car couplers, air lines and electric circuits of railway cars. The present invention relates to systems of this general character and, viewed in one of its aspects, the present invention may be said to have for its object to improve the aforesaid system so as to make certain of the operations so as to secure greater mutuality of dependence of one operation on another and thus reduce the danger of at any time leaving any of the elements or devices to be controlled in positions other than the most desirable or advantageous ones.

Thus, for example, it is desirable to have on each of two cars coupled together a cut-out switch for the electric circuits and, viewed in one of its aspects, my invention may be said to have for its object to produce a simple and novel pneumatic control system which makes it impossible to unlock both of the co-operating car couplers until after both of the cut-out switches have been opened.

It is desirable that the contacts in the electric couplers by means of which the circuits on two cars are connected together be effectively housed and shielded against the weather when the parts are in an uncoupled condition and, in one of its aspects, my invention has for its object to produce a simple and novel pneumatic actuating and controlling means for electric couplers of this type, whereby the door or other closure and a movable contact carrier which must

be projected in the act of coupling will always be compelled to operate in proper time relation to each other.

A further object of the present invention is to provide a simple and novel pneumatic actuating and control system which will prevent both co-operating car couplers on two cars from being uncoupled until after the electric couplers have been uncoupled.

A further object of the present invention is to produce a simple and novel pneumatic actuating and control system for car, air and electric couplers for train line valves and for circuit controlling switches so as to permit all of such elements to be controlled from a single valve on either car.

A further object of the present invention is to produce a simple and novel system employing a combined cut-out switch or circuit breaker and a cross connecting device for the electrical circuits so as to insure that the proper circuits will be connected when cars are turned end for end.

A further object of the present invention is to insure the opening of the main air valves before the closing of the electric circuits, in coupling, and the closing of the air valves before the opening of the electric circuits in uncoupling and to prevent the car couplers from being uncoupled in both cars until the other operations have been completed in uncoupling.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a diagrammatic representation of my improved system for one end of a railway car;

Fig. 2 is a detail illustrating a pressure valve which may be employed in the system;

Fig. 3 is a view similar to Fig. 2 showing the system as applied to the end of a car adjacent to the end on which the system in Fig. 1 is mounted;

Fig. 4 is a top plan view of my improved cut-out and cross connecting switch, to-

gether with the automatic controlling valve and the mechanism for controlling the train pipe valves;

Fig. 5 is a section taken approximately on line 5—5 of Fig. 4;

Fig. 6 is a top plan view of the electric coupler;

Fig. 7 is a front elevation of the electric coupler;

10 Fig. 8 is a section taken approximately on line 8-8 of Fig. 6;

Fig. 9 is a section taken approximately on line 9-9 of Fig. 6;

Fig. 10 is a section taken approximately on line 10-10 of Fig. 6, only the parts immediately adjacent to the plane of the section being shown;

Fig. 11 is a section taken approximately on line 11-11 of Fig. 6; and

20 Fig. 12 is a section of a bleeder valve used.

Referring to Fig. 1 of the drawings, 1 and 2 represent 2 main train pipes forming part of the air brake system of the car. A represents the pneumatic unlocking cylinder for a car coupler. The train pipes on two adjacent cars may be connected together in any suitable way, and the type of car coupler to be controlled by the unlocking cylinder 25 may take any usual or suitable form. The connecting of the main air lines and the mechanical coupling of the cars may conveniently be effected by means of a suitable combined car and air coupling such, for example, as that disclosed in my prior application for combined car and air coupling filed August 13, 1919, Serial No. 317,111, and, since mechanisms of this type are well understood, no detailed illustration or description of the same is included herein. 30 In each train pipe is a controlling valve 3. B represents a pneumatic actuating cylinder for both air valves. C represents a pneumatic device for opening the door of the electric coupler. D is the pneumatic actuating device for projecting the contact carrier of the electric coupler. E represents a valve for controlling the admission of air to the pneumatic device D, the valve E being 35 adapted to be mechanically opened by the door of the electric coupler when said door is opened. F represents a pneumatic trip for releasing the coupler contact carrier when it is desired to uncouple. G is a pneumatic controlling device for a combined cut-out and cross connecting switch. H is an automatic controlling valve. I and K are two manual valves placed at different points on the car and each serving as a master valve from which the connected systems 40 on two cars may be controlled.

Each of the two master valves controls the flow of air from a suitable source of supply. In the arrangement shown, the source of supply is the train pipe 2 and it is con-

ected to the master valves in advance of the main air valves 3 by means of a pipe 4 which is divided into two branches one of which, 5, leads to the valve I while the other, 6, leads to the valve K. The master valves are so constructed, in the particular arrangement shown, that in one position of each air will be permitted to flow into a pipe 7, in another position air will be permitted to flow into a pipe 8, while in a third position the flow of air to both pipes will be interrupted. Furthermore, when air is being supplied to the pipe 7, the pipe 8 will be connected to atmosphere and when air is flowing to the pipe 8 the pipe 7 will be connected to atmosphere. The pipe 7 leads into one end of the elongated cylinder 9 forming part of the automatic valve H. In this cylinder are two connected pistons 10 and 11. Behind the pistons, that is in the opposite end of the cylinder from that to which the pipe 7 is connected, is a spring 12 which tends constantly to force the two connected pistons toward the left; the parts being so constructed, however, that the piston 10 will never move far enough to the left to prevent air from entering the cylinder through the pipe 7. Leading from the cylinder 9, a short distance from the left hand end, is a pipe 13 the receiving end of which is so placed that when the piston is in its left hand position, said inlet end is closed by the piston 10. The pipe 13 has a branch 14 which leads to the pneumatic door-opening device C for the electric coupler and another branch 15 which leads to two terminals 16 and 17 in the electrical coupler; the terminals 16 and 17 being placed in the same horizontal plane and on opposite sides of the longitudinal center of the electrical coupler. The branch 15 also leads to the controlling valve E which is adapted to be opened by the door of the electric coupler. From the valve E extends a pipe 18 one branch of which, 19, is continued to the actuating device D for the contact carrier in the electric coupler while another branch 20 leads into one end of the cylinder 21 of the pneumatic actuating device for the train pipe valves 3, 3. In the cylinder 21 is a piston 22 connected to the valve 3 by a suitable connecting rod 23, so that these valves are opened and closed as the piston travels back and forth. A pipe 25 leads from such a point in the cylinder 21 that the entrance to the pipe is closed when the piston is in the end into which the pipe 20 leads and is opened when the piston is in the opposite end of the cylinder. The pipe 25 opens into the cylinder of the automatic valve H at a point which always lies between the pistons 10 and 11 in this cylinder so that communication is always maintained between the pipe 25 and that portion of the space in the cylinder 9 which lies between the two 130

pistons in the latter. A pipe 26 extends from such a point in the cylinder 9 of the automatic controlling valve that when the two pistons 10 and 11 are moved as far as 5 they will go toward the right, the pipe 26 will communicate with that portion of the space in the cylinder 9 which lies between the two pistons in the cylinder. In other words, the pipes 25 and 26 are placed in 10 communication with each other by the automatic controlling valve when the pistons in the latter are moved toward the right. The pipe 26 extends to and is connected to one end of a cylinder 27 forming part of the 15 pneumatic actuating device G for the combined cut-out and cross connecting switch. A pipe 28 extends from such a point in the cylinder 9 of the automatic controlling valve that when the pistons in this cylinder are 20 in the extreme left hand position, this pipe will be placed in communication with the pipe 25 and, when the pistons are in the extreme right hand position, the inlet end of the pipe 28 will be closed by the piston 10. 25 In other words, the parts are so proportioned that the pipe 25 is connected to either the pipe 26 or the pipe 28, but not to both of them at the same time. The pipe 28 leads into one end of the cylinder 29 of the pneumatic actuating device G. That portion of 30 the piping system heretofore described is or may be used for coupling purposes when one of the master valves is placed in the coupling position so as to admit air to the 35 pipe 7. For the purpose of uncoupling one of the master valves must be placed in position to admit air to the pipe 8. It will be seen that the pipe 8 has a branch 30 leading into that end of the cylinder 21 of the 40 pneumatic actuating device 3 opposite that to which the pipe 20 is connected. Leading from such a point in the cylinder 21 that the inlet end thereof will be closed by the piston 22 when the latter is in the end of 45 the cylinder into which the pipe 30 opens but is uncovered when the piston is in the opposite end of the cylinder, is a pipe 31 having a branch 32 which opens into the opposite end of the cylinder 29 of the device 50 G from that to which the pipe 28 is connected. The end of the cylinder 27, opposite that end to which the pipe 26 is connected, communicates with the corresponding end of the cylinder 29 through a port 55 32^a so that whenever air flows into the cylinder 29 through the pipe 32^a it also flows into the cylinder 27. The pipe 31 also has a branch 33 which leads to the unlocking cylinder A for the car coupler, preferably 60 through a pressure valve 34. The pipe 8 has a second branch 35 which is connected with a branch 36. The common pipe 37 into which the pipes 35 and 36 merge has a branch 38 leading to the trip device F for 65 the contact carrier of the electric coupler and another branch leading to a terminal 39 in the electric coupler. In the pipe 35 is a check valve 40 which prevents the air from flowing through this pipe from the master valve toward the terminal but permits a flow in the opposite direction. In the pipe 36 is a check valve 41 which permits a flow through this pipe toward the terminal 39 but prevents a flow in the opposite direction. It will therefore be seen that air can 70 flow to the terminal 39 through the pipe 36 but not through the pipe 35 and that when air is flowing into the system from the terminal 39, it can pass through the pipe 35 but not through the pipe 36. 75 The equipment at each end of the car is the same and the air terminal 17 is always on the right hand side of the observer as he looks at the end of the car, while the terminal 16 is always on the left hand side of the 80 observer; the terminal 39 being in the center. 85 Fig. 3 illustrates the equipment on the adjacent end of a car adapted to be coupled to that end of the car on which the equipment shown in Fig. 1 is mounted. 90 Assuming that the two cars represented by Figs. 1 and 3 have been brought together in coupled relation so that the air terminals 16 and 17 on one car have been connected to the terminals 17 and 16 on the other car, the 95 terminals 39 have been connected, and the air brake lines coupled together, and that one of the master valves in Fig. 1, for example the valve I, is turned to connect the pipe 7 with the source of compressed air: 100 air will flow from the master valve through the pipe 7 into the left hand end of cylinder 9, forcing the pistons 10 and 11 toward the right until the inlet end of the pipe 13 is uncovered. Air will then flow through the pipe 13 and the branch pipe 14 into the door-actuating device C. Air will also flow through the pipe 15 to the valve device E. When the door of the electric coupler is opened, as will hereinafter be explained, 105 110 air will flow through the valve device E into the pipe 18 and thence through the pipe 19 and into the pneumatic actuating device D for the contact carrier in the electric coupler. In other words, first the door will 115 be opened and, after this has occurred and the door can no longer interfere with the contact carrier if the latter is actuated, air is admitted into the actuating device for the contact carrier. From the pipe 18 air also 120 flows into the pipe 20 and thence into the upper end of the cylinder 21 causing the piston 22 to be forced down and opening the valves 3 in the air brake lines. After the piston 22 has been driven far enough to 125 open the main air valves, the receiving end of the pipe 25 will be uncovered and air will therefore flow through the pipe 25 and into the cylinder of the automatic valve at a point between the pistons in the cylinder, 130

so that air passes onward from the cylinder through the pipe 26 and thence into the cylinder 27 of the cut-out and cross connecting switch, causing the electrical circuits to be closed as will hereinafter be explained. It will therefore be seen that when the master valve is operated, the electric coupler is first placed in the condition to be in operative coupling relation with the coupler on another car, the valves in the train pipes are then opened and, last of all, the main controlling switch is closed. If the electric coupler is not engaged with a co-operating coupler, the air from the pipe 15 would escape through the terminals 16 and 17 and sufficient pressure could not be built up to operate the main air valves and the main switch. When two cars, as represented by Figs. 1 and 3, are coupled together, air flows from the pipe 15 on the first car through the terminals 16 and 17 of the two couplers, into the system on the second car represented by Fig. 3. On this second car the air travels from the terminals 16 and 17 through the pipe 15 and the pipe 14 to the door-opening device C but it does not immediately pass through the automatic valve H because the piston 10 in the latter is in a position to close the adjacent end of the pipe 13. As soon as the door has been opened the air flows through the valve E into the pipe 18 and from the latter pipe through the pipe 19 and into the pneumatic actuating device D for the contact carrier. From the pipe 18 the air also flows through the pipe 20 and into the lower end of the cylinder 21. The piston in the cylinder is forced upwardly, opening the main air valves 3 and thereafter admitting air through the pipe 23 into the space in the cylinder 9 between the valves 10 and 11 and from this space to the pipe 28 which carries the air into the cylinder 29 of the pneumatic actuating means G for the main switch. It will thus be seen that the cycle of operations on the second car is precisely the same as on the first car so far as results are concerned, although the air travels through a somewhat different path on the second car than on the first. It will be seen, however, that on one car one of the cylinders of the main switch-actuating device is energized while on the other car it is the other cylinder that is energized. This serves properly to cross connect the wires of several similar cars having only as many contacts in each coupler as there are circuits to be connected.

The course of the air as it flows through the systems on the two cars during the coupling operations is shown by full line arrows. The course of the air during the operation of uncoupling, which will now be described, is shown by arrows having dotted line stems.

Assuming now that the master valve I in Fig. 1 is turned so as to connect the pipe

8 with the source of air supply and permit the pipe 7 to exhaust to atmosphere, it will be seen that the air is prevented from flowing to the terminal 39 through the pipe 35 on account of the presence of the check valve 40. Air will therefore flow through the branch pipe 30 into the lower end of the cylinder 21, forcing the piston upwardly and closing the main air valves 3. After the piston 22 has been forced up, air is permitted to flow into the pipe 31 and thence through the pipe 32 into the cylinder 29 of the cut-out device G. From the cylinder 29 air flows through the port 32a into the cylinder 27 which was the one previously energized during the coupling operation. Consequently the cut-out switch will be opened, as hereinafter explained. From the pipe 31 the air flows to the pressure valve 34 which prevents it from entering the unlocking cylinder A for the car coupler until the pressure in the system has been built up, preferably high enough to cause the operation of the other actuating devices. Whenever the pressure reaches a predetermined point, air flows into the coupler-unlocking cylinder and unlocks the car coupler. Air also flows from the pipe 31 and pipe 33 through the pipe 36 and from there flows through the pipe 38 into the tripping cylinder F for the contact carrier of the electric coupler. Air also flows directly to the terminal 39 from which it passes into the corresponding terminal on the second car (Fig. 3). On the second car the air flows directly from the terminal 39 to the cylinder of the tripping device F but is prevented from flowing directly to the coupler-unlocking cylinder by reason of the check valve 41 in the pipe 36. Air therefore flows through the pipe 37 and through the pipe 35, the check valve 40 in the latter permitting a flow in the direction away from the terminal 39, and finally enters the pipe 8. From the pipe 8 the air passes through the pipe 30 into the upper end of the cylinder 21, forcing the latter down and closing the main air valves 3. After the piston 22 has been forced down, air flows out of the cylinder through the pipe 31 and thence through the pipe 32 into the cylinder 29 of the main switch, causing the switch to be opened. Air also passes from the pipe 31 through the pipe 33 and pressure valve 34 to the coupler-unlocking cylinder A. It will thus be seen that the car coupler cannot be unlocked on either car before the main air valves on that car have been closed. It will furthermore be seen that by properly proportioning the pressure valves 34 which admit the air to the unlocking cylinders for the car coupler, all of the necessary operations other than the unlocking of the car couplers can be caused to take place before the pressure builds up sufficiently to unlock the car couplers. Also, by properly proportioning the parts, the

main switches may be caused to be opened before the car couplers are unlocked, so that the electric couplers will be dead before the cars can be separated from each other.

5 Since the systems on the two cars are identical with each other, it will be seen that the operations heretofore described will take place if one of the master valves on the second car is operated; the car represented 10 by Fig. 3 in that event becoming the first car and the car represented by Fig. 1 becoming the second car.

In Figs. 4 and 5 I have illustrated in one apparatus the main switch, the automatic 15 valve, and the actuating device for the valves in the train pipes. The device comprises a suitable casing 50 in which are mounted two sets of suitable stationary contact fingers 51 and 52 respectively. One 20 finger of each set is electrically connected to the corresponding finger of the other set as indicated at 53 and to a common terminal 54. The other fingers are connected to independent terminals 55 and 56. At 25 one end of the casing are placed the cylinders 27 and 29, each cylinder containing a piston 57. Piston rods 58 attached to the pistons 57 project through the adjacent wall of the casing and carry on their inner 30 ends plugs 59. It will be seen that when air is admitted to the cylinder 29 through the pipe 28, the plug associated with the piston in that cylinder will connect together the fingers 51 whereas, if air is admitted 35 to the cylinder 27 through the pipe 26, the plug associated with the piston in that cylinder will connect together the fingers 52. Therefore, by carrying the proper wires from the terminals 54, 55 and 56 the 40 circuits will be connected in one way when one cylinder is energized and will be cross connected when the other cylinder is energized; thus making it unnecessary to provide the electric coupler with more contacts 45 than there are circuits to be connected. When air is admitted into the inner ends of both of the cylinders through the pipe 32, both of the pistons will be driven toward the left, as viewed in Fig. 5, opening the 50 circuits. The cylinder 21 of the actuating device B for the valves in the main train pipes 1 and 2 is mounted on the rear end of the casing, the actuating rod 23 projecting out through the ends of the cylinder 55 and being suitably connected to the valve handles 60. The automatic valve device H is placed on top of the casing 50.

In Figs. 6 to 11 inclusive I have illustrated a novel form of electric coupler 60 which may be used to advantage in my improved system. Referring to these figures 61 represents a suitable casing open on the front end and provided with a door 62 for closing said open end. The door is provided at its ends with upwardly- and in-

wardly-projecting flanges or wings 63. Bolts 64 passing through these flanges or wings and the side walls of the casing serve rotatably to support the door. One of the door flanges, as best shown in Fig. 70 11, has a downwardly-projecting lug 65 which is engaged by a spring pressed rod 66 mounted in one side of the casing and under sufficient initial tension to hold the door firmly closed when free to do so. On 75 this same flange of the door, above the hinge axis, is a second lug or ear 67 engaged by a piston rod 68 attached to a piston 69 in the door-actuating cylinder C. When air is admitted into the cylinder C behind the 80 piston through the pipe 14, as heretofore explained, the piston is driven forward and swings the door downwardly so as to open the front end of the coupler casing; the spring pressed plunger 66 being forced back 85 against the tension of its spring.

The other flange of the door, as best shown in Fig. 10, is provided with a shoulder 70 which is arranged at the top and faces rearwardly when the door is open. 90 A gravity dog 71 is pivotally supported in the casing just above this flange of the door, in position to drop behind the shoulder 70 when the door is fully open and hold the door open regardless of the pressure of the 95 air in the pneumatic actuating device. In the top of the casing, just above the flange of the door to which I have been referring, is placed the controlling valve device E. This valve device comprises a suitable 100 chamber 72 which may contain an ordinary poppet valve 73 provided with a stem 74 projecting downwardly through the bottom of the chamber into the path of a lug or cam 75 on the door flange. The parts are 105 so proportioned that when the door is opened, the cam or lug 75 engages with the stem of the poppet valve, forcing the valve off its seat and permitting air to flow downwardly past the valve. The top of the 110 chamber, as heretofore explained, is attached to the pipe 15 while the lower portion of the chamber is attached to the pipe 18. Consequently, when the valve is opened air 115 flows into the pipe 18 and thence to the actuating cylinder for the contact carrier.

The contact elements 76 which are adapted to be engaged by corresponding elements on another coupler are mounted in a suitable carrier 77 arranged within the casing 61; 120 the carrier being preferably provided at any suitable points, conveniently at the four corners, with upwardly-projecting ears 78 through which pass two longitudinal supporting and guiding rods 79 fixed in the casing so as to extend longitudinally thereof. A lug 80 extends downwardly from the top of the casing adjacent to each of the guide rods at a point between the ears 78 slidable 125 on that rod. Surrounding each rod between 130

the rearmost ear 78 and the lug 80 is a spring 81. When the parts are assembled this spring is placed under an initial tension so that when free to do so it holds the carrier 5 in a retracted position. At the rear end of the casing is attached the actuating cylinder D for the carrier. Within this cylinder is a piston 82 having a piston rod 83 projecting forwardly through the rear wall of the 10 casing. Instead of being attached directly to the carrier the piston rod 83 acts on the carrier through a cushioning device which may conveniently consist of a lever 84 hinged at its lower end as indicated at 85, to the carrier at a point below the piston rod and projecting upwardly past the rod. Between the lever and a lug 86 projecting upwardly from the top of the carrier, is a strong spring 87. When air is admitted into the actuating cylinder D, the piston in this cylinder moves forward, pushing the contact carrier outwardly through the open front end of the casing, against the tension of the retracting springs 81 for the carrier. The spring 87 20 is made strong enough to overcome the resistance of the retracting springs and any springs which there may be associated with the individual contacts and the parts are so proportioned that the contact carrier comes to rest either by having the forward ears 78 strike the front wall of the coupler casing or by providing any other suitable stopping means, before the piston has traveled to the limit of its movement. Therefore, the 25 final movement of the actuating piston will serve to compress the spring 87. Above the upper end of the lever 84 is hung a locking dog 88 which is adapted to drop down behind the lever after the contact carrier has been moved forward as far as it will go and the actuating piston has reached the limit 30 of its movement, so that the carrier will be locked in its forward position and will remain there regardless of the pressure of the air in the actuating cylinder.

Above the locking dog 88 is arranged the pneumatic trip device F which consists of a cylinder containing a piston 89 having a piston rod 90 connected to the locking dog 88 so that when air is admitted into the cylinder under the piston 89, the dog will be lifted and free the carrier so that the latter may be returned to its position of rest by means of the retracting springs 81.

It may also be noted that the parts are so proportioned that the doors of two electric couplers in coupled relation to each other may be swung open and shut without interfering with each other. After the carrier 45 has been retracted it is necessary to release the catch which holds the door open in order to permit the spring pressed plunger to close the door. To this end, as best shown in Fig. 10, I have mounted on one side of the contact carrier just below the catch 71 a swing-

ing dog 91. The dog is supported by a pivot 92 placed above its center of gravity so that normally the lower portion of the dog tends to rest against a stop pin 93. On the under side of the catch 71 is a lug having a forwardly-directed cam face 94. The parts are so proportioned that when the carrier moves forward, an upwardly-projecting nose 95 thereon strikes against the rear face of the lug on the catch, causing the dog to be swung upwardly and permitting it to ride underneath the catch without affecting the latter. On the return movement of the carrier the nose of the dog strikes against the inclined face of the lug on the catch and, since the stop pin 93 prevents the dog from swinging in the opposite direction from that caused by a forward movement of the carriage, the dog forces the catch up out of engagement with the shoulder on the door flange and thus permits the door to fly shut.

In the front face of the casing, above the door, are the air terminals 16, 17 and 39 which are adapted to make air-tight connection with the corresponding terminals on another coupler when two such couplers are brought together.

I have heretofore described the system in detail simply in-so-far as the actuating air moves during coupling and uncoupling. Whenever a piston is moved in one direction it is of course necessary for the air behind it to escape. In other words, the air in one part of the system as a whole must be permitted to escape while pressure is being built up in another part. This may be accomplished in various ways. I shall now briefly direct attention to a simple means that I have illustrated for bringing about the necessary venting of the cylinders and pipes in the system.

Whenever one of the master valves is moved into a coupling position, the pipe 8 is connected to atmosphere and therefore, before the piston 22 starts to travel, all the parts of the system connected to the pipes 31 and 35 on the corresponding car are permitted to exhaust through the lower end of the cylinder B as viewed in Fig. 1 and the master valve. When the master valve is turned into its uncoupling position, the pipe 7 is connected to atmosphere, but the upper side of the cylinder of the actuating device B in Fig. 1 is not directly connected to the master valve and I have therefore placed in the upper end of this cylinder a vent 100 which will permit the air to escape as the piston 22 moves upwardly, although the vent is too small to permit sufficient air to escape during a coupling operation to interfere with the successful actuation of the piston 22. The pipe 25 is preferably provided with a pressure valve 101 similar to the valve 34 so as to permit the pressure to build up in the upper end of the cylinder 21 before the 130

air passes through the automatic valve to the cut-out switch. The cylinders in each of the devices A, C, D, F and G are provided with a vent or vents 100 as indicated in the diagram. Further insurance against maintaining pressure in those parts of the system which should be exhausted while pressure is being built up in the other parts may be obtained by placing in the pipe 8 a so-called "bleeder valve" 102, a similar valve 103 being placed in the pipe 15. The purpose of these bleeder valves is to permit the air to escape through the same when the pressure is below a predetermined level, the valves closing, however, when there is an inrush of air such as is produced when the air is admitted to the pipe 8 for uncoupling or to the pipe 15 in coupling.

In Fig. 12 I have illustrated a common form of "bleeder valve" which may be employed. The valve casing is provided with a nipple 104 which may be screwed into the pipe with which the valve is associated. In the casing is a valve 105 controlling an exhaust port 106. On the upper end of the valve is a piston 107 beneath which is a spring 108 which normally holds the valve open. The piston is a loose fit in the casing so that air can flow past it. When the pressure of the air is above a predetermined minimum, the air acts differentially on the piston and forces it down, closing the valve.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. In a system of the character described, an electric coupler having a part movable from one position to another for the purpose of placing the coupler in condition for coupling, an electric switch, an actuator for said switch, and a controller for said actuator associated with said part.

2. In a system of the character described, an electric coupler having a part movable from one position to another for the purpose of placing the coupler in condition for coupling, a train pipe having a valve therein, an actuator for said valve, and a controller for said actuator associated with said part.

3. In a system of the character described an electric coupler having contacts adapted to co-operate with another coupler, a movable door for covering said contacts when the coupler is idle, an electric switch remote from the coupler, an actuator for the switch, and a controller for said actuator associated with said door.

4. In a system of the character described, 65 an electric coupler having contacts adapted to co-operate with another coupler, a movable door for covering said contacts when the coupler is idle, a train pipe having a valve therein, an actuator for said valve, and a controller for said actuator associated with said door.

5. In a system of the character described, 75 an electric coupler having a part movable from one position to another in the act of coupling, an electric switch, a train pipe having a valve therein, actuators for said switch and said valve, and a controller for said actuators associated with said part.

6. In a system of the character described, 80 an electric coupler having a part movable from one position to another in coupling, an electric switch, a train pipe having a valve therein, a switch actuator, a valve actuator, a controller for said valve actuator associated with said part, and controlling means for said switch actuator associated with the valve actuator.

7. In a system of the character described, 85 an electric switch, a train pipe having a valve therein, an actuator for said switch, an actuator for said valve, and means associated with the latter actuator for controlling the actuator for the switch.

8. In a system of the character described, 90 switch mechanism, two pneumatic actuating devices for said mechanism, two air supply pipes, and an automatic valve for opening or closing communication between one of said pipes and one of said devices and simultaneously closing or opening communication between the other of said pipes and the other of said devices.

9. In a system of the character described, 100 a train pipe having a valve therein, a pneumatic unlocking cylinder for a car coupler, an actuator for said valve, and means associated with said actuator for controlling the admission of air to said cylinder.

10. In a system of the character described, 110 a train pipe having a valve therein, an actuating cylinder for said valve, an unlocking cylinder for a car coupler, and means for causing air to flow into the first cylinder and after said valve has been closed to flow from 115 said cylinder into the unlocking cylinder.

11. In a system of the character described, 120 a train pipe having a valve therein, an actuator for said valve including a cylinder and a piston movable therein, an unlocking cylinder for a car coupler, the first mentioned cylinder having a port therein adapted to be uncovered by the piston when it is moved to a position to close said valve, and a pipe leading from said port to said unlocking 125 cylinder.

12. In a system of the character described, 130 a train pipe having a valve therein, an un-

locking device for a car coupler, an electric switch, a device for opening said switch, an actuator for said valve, and means associated with said actuator for controlling said devices.

13. In a system of the character described, a train pipe having a valve therein, an electric switch, a pneumatic device for opening said switch, a pneumatic device for unlocking 10 a car coupler, an actuator for said valve including a cylinder and a piston movable in said cylinder, said cylinder having a port in position to be uncovered by said piston when the latter is moved to a point to close 15 said valve, and a pipe connected to said port and communicating with the aforesaid pneumatic devices.

14. In a system of the character described, a train pipe having a valve therein, an electric switch, a pneumatic device for opening said switch, a pneumatic device for unlocking 20 a car coupler, an actuator for said valve including a cylinder and a piston movable in said cylinder, said cylinder having a port in position to be uncovered by said piston when the latter is moved to a point to close 25 said valve, a pipe connected to said port and communicating with the aforesaid pneumatic devices, and a pressure valve arranged 30 at such a point in the latter pipe that the air from said cylinder is permitted to flow freely into the pneumatic device associated with said switch and is prevented from entering the unlocking device for the coupler 35 until a predetermined pressure has been established.

15. In a system of the character described, a train pipe having a valve therein, an actuator for said valve including a cylinder and 40 a piston movable therein, an air coupler adapted to engage with a co-operating coupler, a controlling valve for admitting air into either end of said cylinder; and a piping system between said controlling valve, 45 said cylinder and said coupler for causing air to enter into the corresponding ends of the cylinders on two adjacent cars whenever the controlling valve on one car is actuated.

16. In a system of the character described, 50 an electric switch mechanism, two actuating devices therefor, an air coupler adapted to co-operate with a corresponding coupler on another car, a master controlling valve, an automatic valve, independent pipes leading from said automatic valve to said actuating devices, piping between said automatic valve and said master valve adapted to be connected by said automatic valve to one of said actuating devices in one position of the automatic valve, and piping from said coupler to said automatic valve adapted to be connected with the pipe leading to the other of said actuating devices in another position of the automatic valve, whereby one of said actu-

ating devices or the other will be operated 65 depending upon whether the air is supplied through the master valve or through the coupler.

17. In a system of the character described, 70 a train pipe having a valve, a pneumatic actuator for said valve, a master valve, an air coupler, a pneumatic coupler-unlocking device; and a piping system connecting said air coupler, said pneumatic unlocking device, said actuating device for the valve in the train pipe, and said master valve for causing said pneumatic actuating device to be operated to close the valve in the train pipe before air is admitted to the coupler-unlocking device, both when air is supplied 75 through the master valve and through the coupler from an adjacent car; whereby the valves in the train pipes on two adjacent cars must be closed before both of the corresponding car couplers can be unlocked. 80

18. In a system of the character described, 85 two switch devices, a pneumatic actuating device for each switch device, an air coupler, a master valve; and a piping system arranged between said actuating devices, said air coupler and said master valve constructed and arranged to cause said pneumatic actuating devices to be operated in one direction when said master valve is placed in one 90 position, to cause one of said pneumatic actuating devices to be operated in the opposite direction when said master valve is placed in another position, and to cause the other pneumatic actuating device to be operated in the direction opposite to the first 95 mentioned direction when air is flowing into the system from the coupler instead of from the master valve. 100

19. In a system of the character described, 105 a train pipe having a valve therein, a pneumatic valve-actuating device, switch mechanism, two pneumatic actuating devices for said switch mechanism, a pneumatic coupler-unlocking device, an air coupler, a master valve; and a piping system between said 110 air coupler, said pneumatic actuating devices, said pneumatic unlocking device and said master valve, for causing said switch mechanism to be opened and closed, said unlocking device for the coupler to be actuated, and the valve in the train pipe to be opened and closed by the proper manipulation of the master valve on either of two cars coupled together. 115

20. In a system of the character described, 120 an electric coupler having a movable door, a pneumatic actuating device for said door, a coupling element arranged within said coupler and adapted to be projected beyond the same when the door is opened, a pneumatic actuator for said element, a master valve, a piping system between said master valve and said pneumatic actuators, a valve 125

- in said piping system for controlling the admission of air to the actuator for said element, and means associated with said door for controlling the latter valve.
- 5 21. In a system of the character described, an electric coupler having a part movable from one position to another for the purpose of placing the coupler in condition for coupling, a switch, pneumatic actuating 70 means for said switch, a master valve, a piping system extending between said master valve and said pneumatic actuating means, a valve in said piping system, and a controller for the latter valve associated with 75 15 said part.
22. In a system of the character described, a part to be actuated, a pneumatic actuator, an air coupler, a master valve, an air pipe leading from the master valve to said coupler, a check valve in said pipe for preventing a flow of air from the valve to the 80 coupler, a connection leading from a point in said pipe between said check valve and said master valve to said actuator, a second 85 20 pipe leading from said coupler to the vicinity of said actuator, said actuator having a port therein leading to said second pipe, said port being so located that when the actuator has been operated to a predetermined 90 25 point by air flowing to the same from the first mentioned pipe the port will be opened to admit said air into the second pipe.
23. In a system of the character described, 95 30 a part to be actuated, a pneumatic actuator, an air coupler, a master valve, an air pipe leading from the master valve to said coupler, a check valve in said pipe for preventing a flow of air from the valve to the coupler, a connection leading from a point in said pipe between said check valve and said master valve to said actuator, a second pipe leading from said coupler to the vicinity of said actuator, said actuator having a port 100 35 therein leading to said second pipe, said port being so located that when the actuator has been operated to a predetermined point by air flowing to the same from the first mentioned pipe the port will be opened to admit said air into the second pipe, said second pipe having a check valve therein for preventing a flow of air from said coupler toward said actuator.
24. In a system of the character described, 105 40 a cylinder, a piston in the cylinder, an air coupler, a master valve, a pipe leading from said master valve to said air coupler, a check valve in the aforesaid pipe to prevent air from flowing from said master valve to said coupler, a connection leading from a point in said pipe between said check valve and said master valve into one end of the cylinder, said cylinder having a port 110 45 therein adapted to be opened by said piston when the latter is moved a predetermined distance from said end, and a second pipe leading from said port to said air coupler.
25. In a system of the character described, 50 a cylinder, a piston in the cylinder, an air coupler, a master valve, a pipe leading from said master valve to said air coupler, a check valve in the aforesaid pipe to prevent air from flowing from said master valve to said coupler, a connection leading from a point in said pipe between said check valve and said master valve into one end of the cylinder, said cylinder having a port 55 55 therein adapted to be opened by said piston when the latter is moved a predetermined distance from said end, a second pipe leading from said port to said air coupler, said second pipe having therein a check valve for preventing a flow of air from said coupler toward said cylinder.
26. In a system of the character described, 60 a cylinder, a piston in the cylinder, an air coupler, a master valve, a pipe leading from said master valve to said air coupler, a check valve in the aforesaid pipe to prevent air from flowing from said master valve to said coupler, a connection leading from a point in said pipe between said check valve and said master valve into one end of the cylinder, said cylinder having a port 65 65 therein adapted to be opened by said piston when the latter is moved a predetermined distance from said end, a second pipe leading from said port to said air coupler, said second pipe having therein a check valve for preventing a flow of air from said coupler toward said cylinder, a pneumatic unlocking cylinder for a car coupler, and a connection between the latter cylinder and said second pipe at a point between the check valve in said second pipe and the first mentioned 70 70 cylinder.
27. In a system of the character described, 75 an electric coupler having a part normally held retracted and adapted to be projected in order to engage with a corresponding part 80 80 on another coupler, a pneumatic actuating device for said part, an air pipe system having terminals adapted to be coupled with corresponding terminals on another car upon impact of two cars and preventing the building up of air pressure in said system until it is coupled to the system on another car, and a valve for admitting air from said system to said actuating device.
28. In a system of the character described, 85 85 an electric coupler containing parts having idle positions and coupling positions, pneumatic actuating means for said coupler, an air pipe system for supplying air to said actuating means having terminals adapted to be coupled with corresponding terminals on another car upon impact of two cars, said system being constructed and arranged so as to necessitate the coupling of the same to another system in order to permit air 90 90

pressure to be built up therein, and a manually-controlled master valve for controlling said system.

29. In a system of the character described, 5 train pipes having terminals adapted to be coupled with corresponding terminals on another car upon impact of two cars, valves in said train pipes, pneumatic actuating means for said valves, an air pipe system 10 having terminals adapted to be coupled with corresponding terminals on another car upon impact of two cars, said pipe system being constructed and arranged to prevent the building up of air pressure therein except when coupled to a corresponding system on another car, and a manually-controlled valve for admitting air to said pipe system and said pneumatic actuating means.

30. In a system of the character described, 20 a pneumatic unlocking device for a car coupler, an air pipe system having terminals adapted to be coupled with corresponding terminals on another car upon impact of two cars, said system being constructed and 25 arranged to prevent the building up of air pressure therein except when coupled to a corresponding system, and a manually-controlled valve for admitting air to said pipe system and said unlocking device.

31. In a system of the character described, 30 a cut-out switch, pneumatic actuating means for said cut-out switch, a pipe system having terminals adapted to be connected to the corresponding terminals on another car 35 upon impact of two cars, said pipe system being constructed and arranged to prevent the building up of air pressure therein except when the car on which it is mounted is coupled to another car, and a manually-controlled valve for admitting air to said system and said pneumatic actuating means.

32. In a system of the character described, 40 an electric coupler having parts adapted to move between idle and coupling positions, 45 pneumatic actuating means for said parts, an air pipe system having terminals adapted to be coupled to the corresponding terminals on another car upon impact of two cars, said terminals being adapted to permit air in 50 said system to flow out into the atmosphere and prevent the maintenance of air pressure in the pipe system except when coupled to a co-operating system, and manually-controlled means for admitting air to said system and said pneumatic actuating means.

33. In a system of the character described, 55 a train pipe having a valve, a pneumatic actuator for said valve, a master controlling valve having a plurality of positions, a piping system connecting said master controlling valve to said device for causing said device to be actuated in one direction when the master valve is in one position and for causing said device to be actuated in the 60 opposite direction when the master valve is

in another position, said piping system having a plurality of terminals adapted to be coupled to the corresponding terminals of a system on another car when two cars are brought together, so as to permit the pneumatic actuating devices on both cars to be operated in one direction or the other from the master valve on either car.

34. In a system of the character described, 70 a cut-out switch, pneumatic actuating means adapted to open and close said switch, a master valve having a plurality of positions, a pipe system for connecting said master valve to said actuating means to cause the switch to be opened when the master valve is in one position and to be closed when it is in another position, said pipe system having terminals adapted to be coupled with the corresponding terminals of a similar system on another car, whereby 75 the cut-out switches on both cars may be opened and closed in unison with each other by the operation of the master valve on either car.

35. In a system of the character described, 80 an electric coupler having parts adapted to move from idle positions into coupling positions, actuating means for said parts, a master valve having a plurality of positions, a pipe system connecting said master valve to said actuating means so as to permit said parts to be moved into their idle positions when the master valve is placed in one of its positions and to be moved into coupling position when the master valve is placed in another of its positions, said pipe 85 system having terminals adapted to be coupled with corresponding terminals of a similar system on another car, whereby the electric couplers on both cars may be actuated in unison in either direction by operating 90 the master valve on either car.

36. In a system of the character described, 95 electrical apparatus, pneumatic actuating means for such apparatus constructed and arranged to operate it in either direction from an idle position to a working position, a train pipe having a valve therein, a pneumatic actuator for said valve, a master valve having a plurality of positions, a piping system connecting said master valve, said actuator and said actuating means so as to cause said actuating means and then said actuator to be operated in one direction or the other when said master valve 100 is placed in one or another of its working positions, said piping system having terminals adapted to be coupled with corresponding terminals on another car, whereby the electrical apparatuses and the valves in the train pipes on both cars will be operated correspondingly and in the same relation to each other when the master valve on either car is moved into one position or another.

37. In a system of the character described,

a train air pipe having a valve therein, a circuit closer, a car coupler unlocking device; separate actuators for said valve, said circuit closer and said unlocking device; and a control system for said actuators constructed and arranged to prevent the circuit closer from being operated, in coupling, before the said valve is opened and prevent said unlocking device from being operated, in uncoupling, until said valve has been closed; and a control system for said actuators constructed and arranged to prevent the circuit closer from being operated, in coupling, before the said valve is opened and prevent said unlocking device from being operated, 10 in uncoupling, until said valve has been closed.

38. In a system of the character described, a train air pipe having a valve therein, a circuit closer, a car coupler unlocking device; 15 separate actuators for said valve, said circuit closer and said unlocking device; and a control system for said actuators constructed and arranged to prevent the circuit closer from being operated, in coupling, before the said valve is opened and prevent said unlocking device from being operated, in uncoupling, until said valve has been closed; and a control system having terminals adapted to be connected to the terminals of a corresponding system on another car and connect the two systems in such relation to each other that the car couplers are prevented from being unlocked on both cars until after the air valves and the circuit closers have been operated on both cars. 20 25

In testimony whereof, I sign this specification.

HERBERT E. VAN DORN.
